Design for Parlor Stove Plates,
by Luther W. Harwood, of Troy, N. Y.,
Assignee to Philo P. Stewart, of Troy, N. Y.

Witnessed, Patented Jan'y 7, 1868. Design.

Alphonse Reed
Austin T. Park.

Luther W. Harwood

Dec. 1510

Luther W. Harwood, of Troy, N.Y.
Assignor to
Phil S. Stewart, of same place.
Letters Patent No 1510, dated Jan. 7, 1862.

The schedule referred to in these Letters Patent and making part of the same.

To all whom it may concern:

Be it known that I, Luther W. Harwood, of the city of Troy, in the County of Rensselaer, and State of New York, have invented or produced a new and original Design for Parlor-Stove Plates, and I do hereby declare that the following is a full, and exact description of the same, reference being had to the annexed photographic drawings, in which -

Fig. 1, represents the elliptical or oval top. plate.

Fig. 2, the feed door and its frame.

Fig. 3, the oval top. plate of the base, and

Figs. 4 and 5, side plates of the base, all of a parlor-stove having an elliptical barrel extending between the plates shown by

Wes. 15 10

Fig. 1 and 3.

My said ornamental design for parlor stove plates is characterized by the arrangement of the series of compound gothic arches and ornaments, a, and rows of projections, b, and c, with and upon the mouldings d, e, and f, on the top plate Fig. 1; the series of gothic arch-ornaments g, disposed along the border of the door frame, Fig. 2; the rows of gothic arch-ornaments, h, and projections i, on the ledge or moulding, j, of the top plate, Fig. 3, of the base of the stove; and the formation of the side plates, Figs. 4 and 5, of the base of the stove, with central oval, check work panels, l, surrounded by rope-like mouldings, k, within rectangular panels formed by scalloped mouldings, m, with the ornaments n, in the corners: - as shown by the annexed photographs.

What I claim as new and of my invention or production and desire to secure by Letters Patent, is a design for parlor stove plates having the ornamental features above described.

Witnesses,

Alphonse Picard,

Austin F. Park. }
